DRIVING-LOCKING MECHANISM

Guy E. Swartz, Detroit, Mich.

Application March 2, 1931. Serial No. 519,644

13 Claims. (Cl. 192—8)

My invention relates to means for driving a mechanism and releasably locking the mechanism against rotation.

Objects of my invention are:

- 5 To provide a simple, effective and efficient locking mechanism;
- To provide easy release from a locking condition thereof;
- To provide automatic locking and releasing 10 thereof by and during the operation of the device which has the locking mechanism;
- To provide locking shoes which extend substantially along the entire length of the surface which is used for locking;
- 15 To provide a moving means for the shoes which does not wedge a member between inclined walls;
- To provide a moving means for the shoes which acts on both ends of each shoe;
- To provide a moving means for the shoes which 20 acts compensatingly on all of the shoes;
- To provide grooves in the shoes so that the mechanism can be profusely lubricated for easy operation and preservation thereof without having a locking effect decreasing film of lubricant 25 between the shoes and the surface contacted by the same;
- To provide a direct drive for the device using the locking mechanism and to use the same drive to effect the operation of the locking mechanism;
- 30 To provide symmetry in the structure so that the locking mechanism can be used for locking a device against rotation in either direction.

Other objects will appear or will become apparent or obvious upon an inspection of this 35 specification and the accompanying drawing.

I attain my objects by the mechanism illustrated in the accompanying drawing in which:

Fig. 1 is a perspective view of a work clamping jig having a driving-locking mechanism embodying my invention.

Fig. 2 is a transverse section of the driving-locking mechanism of Fig. 1; the section being taken on the line 2—2 in Fig. 4 showing the relation of the driving prongs and the locking shoes and the rotatable member and the casing when the device is in clamping driving position.

Fig. 3 is a transverse section of the driving-locking mechanism, taken on the line 3—3 in Fig. 4, showing further relation between the shoes and the rotatable member and the casing; the driving prongs being shown in dotted lines in lock releasing and reverse driving or clamp releasing position.

Fig. 4 is a longitudinal section taken on the

line 4—4 in Fig. 2 showing further relations between the elements of the locking mechanism.

Fig. 5 is a perspective view of the driving member.

Fig. 6 is a perspective view of one of the locking shoes.

Similar reference characters refer to similar parts throughout the views.

The jig itself comprises the movable clamp plate A having the tool guiding bushing 10 therein and the two guide posts 11 depending therefrom and being guided in the base B.

The shaft C is journaled in the base and has the teeth 12 in mesh with corresponding teeth on the posts 11 so that a rotation of the shaft 70 moves the posts longitudinally and thereby moves the plate A toward and away from the base for clamping and unclamping of work.

The casing D is fixed on the base and is unrotatable and has the circular bore 13 concentric 75 with the axis of the shaft C which has the end 14 extending into the casing.

The member or disk E is keyed onto the shaft end 14 so that the same rotates with the shaft and the shaft rotates with the disk according to 80 which one of these parts is rotated.

The driving slots 15, three in the present instance, equally spaced and all of the same size, are provided in the outer surface of the disk E and extend all the way across the same although 85 they could extend inwardly from one end only sufficiently deep for the driving prongs described below. The spaces not occupied by the driving prongs being used for lubrication storage purposes.

The grooves 16 also extend all the way across the disk and are also equally spaced and of the same size.

The outer circumferential surface of the disk 95 is concentric with the axis of the shaft.

The locking shoes F, three in number in this instance, each has the circular surface 17 of a curvature suitable to the curvature of the bore in the casing. The locking shoes are of sufficient length to substantially extend all the way around on the surface of the bore; there being only a narrow space 18 between the ends thereof.

Each of the shoes has the bevel surface 19 on each end thereof and also has the radial slots 20 intermediate the longitudinal ends and extending into the sides thereof sufficiently deep to accommodate the driving prongs described below. The slots 20 are provided on each end so that the shoes can be reversed.

The grooves 21 are provided in the surface 17 to 110

retain lubricant and to receive excessive lubricant from between the surface 17 and the bore 13.

Applicant has found that lubrication is necessary for a locking mechanism as shown, that even a hardened and ground bushing in the casing requires, or at least should have, lubrication and that such lubrication presents a film of lubricant between the shoes and the casing sufficient to reduce the locking effect of the shoes and promotes slipping of the lock.

The grooves 21 prevent the formation of such a film and thereby reduce if not entirely overcome these disadvantages in that there usually is some endwise movement of the shoes which tends to 15 scrape excessive lubricant from the bore in the casing and deposit the same in the grooves and furthermore, if the walls of the grooves did not so scrape off this surplus lubricant, the radial movement of the shoes will squeeze it out from 20 between the contacting surfaces and into the grooves since the individual contacting surfaces on the shoes are each comparatively narrow and the surplus lubricant needs to travel only a very short distance to reach the groove for disposition 25 thereof.

Furthermore, applicant has found that the provision of the grooves provides a much better gripping effect between shoes and a surface contacted by the same independent of lubricant.

30 The invention provides for profuse lubrication without detrimental effects to the gripping of the shoes so that bushings and the like can be eliminated and the shoes can operate directly on the material of the casing, usually a cast material.

35 I prefer to use the shoes directly against the casing material, to bore the casing fairly smooth, without grinding, and let the shoes and the bore wear to a seat and thereby get better gripping results than with ground contacting surfaces 40 and reduce cost of production.

The shoes are journaled loosely in the bore 13 and on the outer surfaces 22 of the disk E so that the same can move longitudinally between the same and so that there is no wedging of the 45 shoes between inclined surfaces.

There is a toggle structure between the shoes and the disk comprising three strut-like members G, duplicates and equally spaced, each having the end 23 thereof rounded and seated in a 50 round bottom slot extending across the disk and the end 24 thereof abutting onto the corresponding bevel faces 19 of two adjacent shoes.

The longitudinal axes of the members G are inclined to a radial axis of the disk; the ends 23 55 being in the lead when the disk is rotated in the direction indicated by the arrow thereon.

The members G are not physically attached to any part of the mechanism and the round bottom slots for the ends 23 thereof are open at both 60 ends so that a locking action can be effected against rotation of the shaft in a direction opposite the arrow by merely sliding the members G out of the positions shown, then moving the shoes in the direction of the arrow until the 65 members G can be inserted with the angularity reversed from the position shown and thereby render the lock mechanism operable for locking either against right or left hand rotation of the shaft.

70 The three springs 25 are mounted in the disk and each extends into the corresponding groove 16 and endwise abuts the corresponding member G as shown and tend to normally and constantly hold the members G onto the bore in the casing 75 by tending to decrease the angularity between the

axes of the members G and the radial axis of the disk.

The driving or operating member H, operated by the handle I thereon, is journaled on the shaft C, has the flange 26 closing the open end of the casing, and also has the three driving prongs 27 each extending into the corresponding slots 15 in the disk and the slots 20 in the corresponding shoes.

Upon movement of the handle in the direction indicated by the arrow on the disk, the handle rotates on the shaft, taking up lost motion. The faces 28 of the driving prongs 27 then contact the walls 29 of the slots 15 and rotatively move the disk and thereby rotates the shaft which, in turn, moves the clamping plate for clamping of work.

While the disk is so rotating, the locking shoes are also moving rotatively and, due to the members G being inclined backwards of the direction of rotation, there is very little friction between the shoes and the bore in the casing so that the entire locking mechanism can rotate freely in the casing.

When the clamping plate contacts the work, 100 there is a resistance against further movement of the plate and consequently against rotation of the shaft and the disk thereon.

A continuation of the same operation by the handle takes up whatever lost motion may exist 105 in the device and further force or pressure applied to the handle puts rotative strain onto or into the parts of the locking mechanism and also creates a clamping pressure between the clamping plate and the work. The force applied to 110 the handle can be made as heavy as desired for clamping the work.

As soon as pressure on the handle is released and movement of the handle stops, there is nothing to create an inward movement of the shoes 115 and the springs 25 at once move the members G toward less angularity between the axes of the members G and the radial axis of the disk and thereby seating the shoes firmly on the bore in the casing.

The strain in the parts and the clamping naturally tend to find release and thereby exert a rotative pressure on the ends 23, reversely of the arrow, and thereby direct this strain radially outwardly and against the casing in a toggle action 125 and thereby producing an effective lock of the clamping mechanism against voluntary reverse rotation of shaft and release of clamping pressure between the clamping plate and the work.

When additional pressure is brought onto the 130 clamping plate in the same direction as the direction of the original pressure, the pressure on the ends 23 of the toggle members G is correspondingly increased with consequent increase of pressure between the shoes and the casing and consequent increase of locking effect.

The strain and pressure existing when work is clamped tends to rotate the shaft and the disk reversely but the direct and positive connection or abutment of the toggle members G on the 140 disk and the shoes and the strain in the parts permits of very little reverse rotation of the shaft so that the clamping is practically unaffected if the shaft did rotate slightly.

When this same directional pressure on the 145 plate actually produces a reverse rotative movement of the shaft, the ends 23 of the toggle members move reversely of the arrow and thereby increase the locking pressure between the shoes and the casing according to the additional pres- 150

sure applied to the clamping plate for more effective frictional engagement of the shoes with the casing and consequent more effective locking of the mechanism.

5 In some instances, the driving faces 28 may contact the ends of the shoes and thereby advance the ends 24 of the toggle members with consequent reduction of angularity between the axes of the toggle members and the radial axis 10 and consequent locking abutment of the shoes on the casing.

Upon a reverse movement of the handle, the faces 30 on the prongs 27 first contact the walls 31 on the slots 20 and move the shoes rotatively and reversely to the arrow and thereby moving the ends 24 of the toggle members reversely and thereby increasing the angularity between the axes of the toggle members and the radial axis of the disk and thereby radially releasing the shoes from the bore in the casing.

15 Further reverse movement of the handle contacts the driving faces 30 on the prongs 27 onto the walls 32 on the member E and thereby reversely rotates the disk and the shaft and moves the clamping plate out of clamping position.

20 When the handle is standing still in any position thereof, the springs 25 at once effect an automatic locking of the mechanism which is automatically released upon a movement of the handle in either direction.

25 Each of the shoes can move rotatively individually of the other shoes so that each can move compensatingly in relation to the others. Each toggle member engages two of the shoes at the ends thereof through bevel faces so that all of the shoes are moved radially in an expanding manner and all of the shoes are contacted on the casing equally or with the same force and the entire contacting surface 17 engages the bore in the casing since the support of the shoes is located at each end thereof and there is no possibility of the shoes tilting or otherwise preventing full contact of the surface 17 on the wall of the casing.

30 The device shown and described attains the objects sought to be attained.

I am aware that structural and functional changes can be made in the parts and in the arrangements thereof shown and described within the scope of my invention and the appended claims; therefore, without limiting myself to the precise structure and function and arrangement of parts as shown and described,

35 I claim:

1. A driving-locking mechanism for an operable device including an unrotatable casing having a circular bore, a rotatable member of the operable device extending into said bore, a locking shoe against said bore, a toggle member between said member and said shoe, a spring acting on said toggle member to normally hold said shoe in locking contact on said bore, said toggle member being adapted to augment the action of said spring upon a tendency of said operating member to rotate reversely, and a driving member engaging said rotatable member for rotation thereof and automatic release of said shoe for rotation thereof with said rotatable member and engaging said shoe for automatic release movement thereof from a locking position thereof.

2. In a driving-locking mechanism a locking member having a slot in a side thereof, a rotatable shaft, a disk on said shaft and rotatable therewith and having a slot in a side thereof, a driving member journaled on said shaft and having a prong extending into said slots to engage the

respective side walls thereof for rotating said disk and said shaft in corresponding directions and for locking and releasing of said locking member.

3. In a driving-locking mechanism, a rotatable shaft, a disk on said shaft and rotatable therewith and having a slot in an end surface thereof, a driving member journaled on said shaft and having a prong extending into said slot to engage the side walls thereof for rotating said disk and said shaft in corresponding directions, and a locking mechanism operated by rotation of

80 said driving member comprising, locking shoes circularly adjacent each other and radially against a casing, a normally inclined strut member having one end thereof rockably seated in

85 said disk and the other end thereof engaging the adjacent ends of said shoes, a spring in a pocket of said disk and abutting said strut member to normally reduce the inclination thereof to

90 retain said shoes against the casing, and rotation of said disk through said shaft further reducing the inclination of said strut to increase the locking against the casing.

4. In a driving-locking mechanism, a locking member having a slot in a side thereof, a rotatable shaft, a disk on said shaft and rotatable therewith and having a slot in an end surface thereof, a driving member journaled on said shaft and having a prong extending into both of

95 said slots to engage the side walls of said slot in said disk to rotate said disk and said shaft in

100 corresponding rotative directions and to engage said slot in said locking member to lock the same, and said locking member normally locking said disk and said shaft against self rotation independent of said driving member.

5. In a driving-locking mechanism, a rotatable shaft, a disk on said shaft and rotatable therewith and having a slot in an end surface thereof, a driving member journaled on said shaft and having a prong extending into said slot to engage the side walls thereof to rotate said disk and said shaft in corresponding rotative directions, and a locking mechanism normally locking said disk and said shaft against rotation independent of said driving member and comprising

105 said disk and the other end thereof engaging the adjacent ends of said locking shoes to retain said disk and said shaft against rotation independent of said driving member, and means operated by said prong to more tightly lock said shoes against said wall and to release the same from

110 the tight locking.

6. In a driving-locking mechanism, a driving mechanism adapted to directly contact a driven mechanism for driving the same in opposite directions, and a locking mechanism comprising a

115 casing having a bore, locking shoes circularly adjacent each other and radially adjacent inwardly of the wall of said bore, an inclined strut normally retaining said driven mechanism against

120 rotation independent of said driving mechanism, and means operated by said driving mechanism to more tightly lock said shoes against said wall and to release the locking upon corresponding

125 operation of said driving mechanism.

7. In a driving-locking mechanism, a driving mechanism adapted to directly contact a driven mechanism for driving the same in opposite directions, and a locking mechanism comprising a

130 casing having a bore, locking shoes circularly adjacent each other and radially adjacent inwardly of the wall of said bore, an inclined strut normally retaining said driven mechanism against

135 rotation independent of said driving mechanism, and means operated by said driving mechanism to more tightly lock said shoes against said wall and to release the locking upon corresponding

140 operation of said driving mechanism.

8. In a driving-locking mechanism, a driving mechanism adapted to directly contact a driven mechanism for driving the same in opposite directions, and a locking mechanism comprising a

145 casing having a bore, locking shoes circularly adjacent each other and radially adjacent inwardly of the wall of said bore, an inclined strut normally retaining said driven mechanism against

150 rotation independent of said driving mechanism, and means operated by said driving mechanism to more tightly lock said shoes against said wall and to release the locking upon corresponding

- adjacent each other and radially adjacent inwardly of the wall of said bore, an inclined strut between a part of said driven mechanism and the adjacent ends of said shoes, a spring tending to reduce the inclination of said strut to move said shoes against said wall to retain said driven mechanism against rotation independent of operation thereof by said driving mechanism, and means operated by said driving mechanism to more tightly lock said shoes against said wall and to release the locking upon corresponding operation of said driving mechanism.
8. In a driving-locking mechanism, a driving mechanism adapted to directly drive a driven mechanism in opposite directions, said mechanism including a disk on a part of said driven mechanism and having a slot in a side thereof, a prong on said driving mechanism and extending into said slot to engage the side walls thereof to drive said driven mechanism in either direction, and a locking mechanism between said disk and a casing normally locking said driven mechanism against rotation independent of operation thereof by said driving mechanism and engaged by said prong to more firmly lock and to release the locking by operation of said driving mechanism.
9. In a driving-locking mechanism, a driving mechanism adapted to directly drive a driven mechanism in opposite directions, said mechanism including a disk on a part of said driven mechanism and having a slot in a side thereof, locking shoes circularly adjacent each other and radially adjacent to a wall of the mechanism and each having a slot in a side thereof radially in substantial alignment with said slot in said disk, a prong on said driving mechanism and extending into said slots in the disk and in the shoe to contact the walls of said slots to operate said driven mechanism and said shoes in timed relation to each other to finally lock said driven mechanism and to release the locking.
10. In a driving-locking mechanism, a driven mechanism, a driving mechanism for said driven mechanism, a locking means for said driven mechanism, a slot and prong engagement between parts of said driven and driving mechanisms to directly drive said driven mechanism in either direction, and a slot and prong engagement be-
- tween parts of said driven mechanism and said locking means to lock said driving mechanism against rotation at the end of an operation by said driving mechanism and to release the locking at the beginning of an operation by said driving mechanism.
11. In combination a reciprocally movable clamp and operating mechanism therefor including a shaft normally locked against reverse rotation and in operative connection with said clamp to move the same, a disk secured to said shaft and having a slot in a side thereof, and a driving member for said disk having a prong extending into said slot to release said normal locking and to engage the side walls of said slot for rotation of said shaft in either direction.
12. In combination a reciprocally movable clamp and an operating and locking mechanism therefor including a shaft in operative connection with said clamp to move the same, a disk normally locked against reverse rotation secured to said shaft and having a slot in a side thereof, a driving member for said disk having a prong extending into said slot to release said normal locking and to engage the side walls thereof for rotation of said shaft in either direction, and a locking mechanism to releasably lock said shaft and clamp against reverse rotation upon pressure from said clamp.
13. In combination a reciprocally movable clamp and operating mechanism therefor including a shaft in operative connection with said clamp to move the same, a disk secured to said clamp to move the same, a disk on said shaft and normally locked against reverse rotation and having a plurality of slots in a side thereof, a driving member for said disk having prongs each extending into one of said slots to engage the side walls thereof for rotation of said shaft and clamp in either direction, and a locking mechanism including strut members all inclinedly mounted in one direction and adapted to lock said mechanism against reverse rotation through pressure brought upon the clamp and to release the locking and move the clamp reversely upon a reverse rotation of said crank.
